ABSTRACT OF THE DISCLOSURE

A spinneret assembly particularly suitable for melt-spinning filaments of noncircular cross section is provided. The spinneret is made of a solid plate having an extrusion face and a melt face. At least one orifice extends between the faces and is provided with a counterbore melt receiving portion and an extrusion portion presenting a plurality of elongated slots. In the counterbore a solid discrete spheroid is positioned to divert the flow of the melt toward the extremities of the elongated slots. This arrangement makes possible a convenient extension of the number of noncircular cross-sectional shapes that one can produce in filaments made using a given spinneret.

BACKGROUND OF THE INVENTION

Recently to alter the properties thereof the cross-sectional shape of man-made filaments has been modified from normally round to a variety of noncircular configurations. Filaments having noncircular cross sections have been melt spun from many differently shaped spinneret orifices. However, the number of different shapes that one can obtain from a given orifice is limited by restrictions in changes that can be made in the spinning conditions to overcome the tendency of the extruded stream to become round regardless of what cross-sectional shape the spinneret passage may have imparted. The actual shape of the filament shape resembles the cross section of the spinneret orifice from which the filament extrudes to a greater or lesser degree, depending upon the specific spinning conditions. It is well recognized, for example, that the use of very high viscosity polymer and very rapid quenching of the extruding filaments favors retention of the noncircular shape similar to the orifice. For a given size and shape of spinneret orifice, however, only a relatively narrow range of spinning conditions are operable practically; hence, when the desired filament cross-sectional shape is not achieved, the only practical solution heretofore has been to make a new spinneret having different dimensions that will yield the required filament shape. The obvious drawback to this is that noncircular capillaries have been and continue to be difficult to make and are quite expensive. In accordance with the present invention, a very simple procedure of extending the range of filament shapes possible with a given spinneret under practical operating conditions is provided.

In the prior art it has been proposed that the more open central area of the orifice be blocked by inserting a core or pin in the orifice. In practice such cores must be very accurately machined and exactly centered or the polymer flow is severely distorted, causing malformed filaments. Such pins have been of no known practical utility even in hollow filament spinning and are too expensive for general use.

Therefore, it is an object of the present invention to provide a spinneret adapted for spinning filaments having a larger range of non-circular cross sections than one can normally obtain for a given orifice design.

2**SUMMARY OF THE INVENTION**

A spinneret for making filaments of noncircular cross section is provided and comprises a solid plate having a spinning fluid delivery face and an extrusion face. At least one orifice extends between the faces to provide a passageway for extrusion of the fluid into filaments. The orifice has a portion of larger cross-sectional area adjacent the extrusion face and a portion of smaller cross-sectional area adjacent the delivery face. The bounding wall defining the orifice encloses a plurality of elongated slots at the extrusion face. Detachably positioned in the portion of larger area is a spheroid for diverting the flow of the spinning fluid toward the extremities of the elongated slots. This provides a simple expedient for extending the operable range of a noncircular spinneret orifice.

DESCRIPTION OF THE DRAWING

The invention can best be understood by reference to the following description taken in conjunction with the accompanying drawing in which:

FIGURES 1 and 2 are schematic lateral section views through a single spinneret orifice or capillary, including the counterbore, a spherical ball being shown in the counterbore upstream of the noncircular capillary portion; and

FIGURES 3, 4 and 5 illustrate spinneret orifices and typical but enlarged cross sections of filaments spun through these orifices; *b* figures are illustrative of the filament sections spun directly from the spinneret orifices, *a* without the polymer diverting ball; and the *c* figures are illustrative of the filament sections spun with a spherical ball in the counterbore.

With reference to FIGURE 1, there is shown a segment of a spinneret 1 usually made of a solid metal plate of thickness suitable to withstand normal extrusion pressures. The spinneret is adapted for inclusion in a standard spinning block assembly and has at least one spinning orifice and in some instances several hundred orifices. For simplicity of illustration, the views in FIGURES 1 and 2 each show only one orifice 2. The spinneret has a spinning fluid delivery face 3. The fluid in melt spinning operations is molten polymer which seeks the exit provided by the orifices. The arrows 4 indicate the flow path of spinning fluid through the orifice to the discharge side of the spinneret having extrusion face 5. Orifice 2 defined by a bounding wall has an upper counterbore portion 6 of larger cross-sectional area and has a capillary portion 7 of smaller cross-sectional area. The bounding wall at the extrusion face encloses a plurality of elongated slots best seen in FIGURES 3a, 4a and 5a. An unannexed spheroid taking the preferred form of a metal ball 8 is inserted in the counterbore portion.

Metal spherical balls are preferred because of ready availability, and the higher thermal conductivity of the metal helps to equalize the temperature of molten polymer entering the capillary. Ball bearings of various alloys including common stainless steels, such as type 316, can be used and are manufactured to extremely close dimensional tolerances.

The bottom of the counterbore for noncircular orifices is preferably made flat in order to have a reproducible constant capillary length as illustrated in FIGURE 1. However, most twist drills have at least a slight conical point to center the drill; a counterbore drilled with such standard drill is illustrated in FIG. 2, and is altogether satisfactory when a ball is placed as shown in the counterbore; without the ball, polymer channels severely into the center of this counterbore which is much inferior to the flat-bottomed counterbore.

It has been found that the spherical ball is self-centering in the polymer stream so that the balls can be merely

dropped in the counterbores when the spinneret pack is assembled. The ball will be centered even when there is a small burr on the counterbore bottom, provided the burr is not too large and the ball is not too small. It is believed that the centering of the ball is due to the lateral hydrodynamic forces generated by the flowing polymer. When the ball is off center, for example, polymer velocity will be higher on the wider side of the annulus where the polymer tends to channel. The pressure in the high velocity region is lower than in the low velocity region; this imbalance in pressure causes the ball to shift until the pressure is equalized or the velocity distribution is symmetrical around the ball which occupies the central position.

The flow distribution of the polymer depends upon the diameter of the ball so that several different distributions may be easily attained with a given spinneret design. In general, more polymer flows toward the ends of the slots away from the central opening. This not only increases the filament shape definition for a given set of spinning conditions, but the stability of the extruding polymer jet is also much improved, and the jets extrude more nearly normal to the face of the spinneret.

The diameter of the ball in relation to the counterbore or other confining channel must be such that the minimum unobstructed transverse cross section of the polymer stream is at least twice as great as the cross sectional area of the capillary. If the ball is too large to satisfy this condition, the pressure drop and drag force on the ball becomes so great that ordinarily the counterbore bottom cannot support the resultant force without being deformed. For circular section counterbores this limitation is conveniently expressed algebraically:

$$A_m = \frac{\pi}{4} (D_c^2 - D_b^2) \geq 2A_o$$

wherein,

A_m = Minimum unobstructed transverse section
 D_c = Diameter of counterbore
 D_b = Diameter of spherical ball
 A_o = Cross-sectional area of the capillary

Usually it is preferable for the minimum unobstructed section to be not less than about four times the cross-sectional area of the capillary.

The lower limit of the size of the spherical ball is determined by the size of the open area at the center of the capillary. The ball should not be so small that its bottom boundary projects into the capillary more than about one-half the axial length of the capillary. When the ball is seated much lower than this there is a tendency to trap air in the extruding polymer which distorts the filament section and forms bubbles or erratic voids in the filament.

The spherical balls useful according to the invention are not only initially inexpensive but also are reusable. When the spinneret is conventionally heat-cleaned, the balls are also cleaned and are ready for reuse. If acid-cleaning is utilized, the material of the ball should, of course, be selected to withstand the corrosive action of the acid.

With reference to FIGURE 3a, a fragment of spinneret 1 is shown that is suitable for melt spinning synthetic thermoplastic filaments such as nylon and the like. The extrusion face 5 has a capillary 7 suitable for spinning a filament having a three-sided cross section. FIGURE 3b is a cross section of a filament that one can produce using such spinneret and the illustrated trifurcated capillary. When the same capillary is used wherein a ball is placed in the counterbore, a filament having a more defined cross section is produced. Under the same spinning conditions cross section shapes intermediate of those in FIGURE 3b and FIGURE 3c can be obtained by varying the size of the ball and/or other factors.

With reference to FIGURE 4a, a fragment of a spinneret 1 is shown. In this case the capillary 7 in the extrusion face 5 has five radially extending and elongated slots. FIGURE 4b is a pentagonal section of a filament produced using this structure without the spinning fluid diverting ball. FIGURE 4c is a section of a filament produced under like conditions employing the same spinneret except that a ball is used. Again, under like spinning conditions filament shapes intermediate of those in FIGURE 4b and FIGURE 4c can be obtained by varying the size of the inserted ball.

With reference to FIGURE 5a, a fragment of a spinneret 1 is shown. In this case the capillary 7 in the extrusion face 5 has ten radially extending and elongated slots. FIGURE 5b is a ten-lobed section of a filament produced using this structure without the spinning fluid diverting ball. FIGURE 5c is a section of a filament where a ball is used. Again, under like spinning conditions, filament shapes intermediate of those in FIGURE 5b and FIGURE 5c can be obtained by varying the size of the inserted ball.

By the method of the invention the useful range of any given spinneret with noncircular orifices is greatly extended making it possible to spin filaments under moderate conditions that would not be possible even under extreme conditions without a permanent modification of the spinneret. Even in the case of non-intersecting slot spinnerets used for spinning hollow filaments, the jet stability was observed to be appreciably improved by polymer flow redistribution due to a ball in each counterbore.

The following examples illustrate the invention.

Example I

35 A 34-hole spinneret intended to spin filaments having a triangular cross section was made using a standard type 430 S/S (stainless steel) blank 0.312 inch thick by 3.44 inches diameter. Thirty-four flat-bottomed counterbores 0.098 inch in diameter formed from the back side 40 of the spinneret were arranged in groups of 17 on each side of a principal diameter. Capillaries 20 mils long and having a cross section as illustrated in FIGURE 3a were formed. Measured from the center of the orifice, three equispaced slots 2.6 mils wide by 32 mils long were formed in which the intersection of adjacent slots was 45 rounded off by a circular arc of 20 mil radius.

The 34-hole spinneret was assembled in a conventional spinneret pack and was installed in a standard grid-melting spinning machine. Machine conditions were set to spin a 260 denier-34 filament yarn at a windup speed of 50 350 y.p.m. (yards per minute). Filaments were cooled by a crossflow of air at 22° C. Flowing at 55 ft./min. lineal rate. The grid unit was operated at 292° C. Nylon 66 polymer flake having a standard relative viscosity of 55 37 in 90% formic acid and containing 0.03% TiO₂ was charged to the spinning machine.

Physical operability of the spinneret was satisfactory but the cross section of the spun filaments was almost circular. Spinning conditions were varied widely, such as increasing air flow, reducing spin unit temperature, and changing windup speed and substituting polymer of higher relative viscosity, but even under the most extreme conditions filament section varied only slightly from circular or had irregular indented sides.

65 The 34-hole spinneret was cleaned and reassembled in the spinneret pack. Steel ball bearings 0.060 inch in diameter were placed in the counterbores of one group of 17 capillaries. In these counterbores the minimum unobstructed transverse area was about 4700 sq. mils compared with 320 sq. mils of the orifice; i.e., $A_m = 4700$ 70 and $A_o = 320$. The spinneret pack was again installed in the spinning machine newly set to spin 260 denier-17 filament yarn at 300 y.p.m. Each group of 17 filaments was wound on separate bobbins. Nylon 66 polymer flake having nominal relative viscosity of 40 was charged to the 75

spinning machine and extruded at a temperature of 292° C.

The different appearance of filaments extruding from capillaries having the ball upstream was immediately apparent. The jets of polymer were much straighter, flowing cleanly away from the spinneret and presenting much more stable movement in the cooling air stream.

Cross sections of the spun filaments showed that those spun from the unobstructed capillaries were a much rounded-out curvilinear triangle that differed relatively little from a circular section, as illustrated in FIGURE 3b. Filaments from capillaries with balls upstream in the counterbores had a well-formed triangular section with slightly convex sides and only moderately rounded corners, as illustrated in FIGURE 3c.

Samples of each type of 260-17 yarn after drawtwisting was knitted into flat fabric. Fabric containing the degenerate triangular section filaments was somewhat more lustrous than standard circular filaments but not otherwise different in appearance. On the other hand, filaments with the well-formed triangular sections imparted a high degree of scintillating luster and considerably greater cover than circular filament yarns.

Example II

A 6-hole spinneret 2.03 inch diameter by 0.189 inch thick was prepared to produce 5-point star monofilament yarn. Six counterbores of 0.094 inch diameter were drilled from the backside of the spinneret forming a flat bottom and leaving metal to provide a capillary length of 13 mils. Capillaries were formed of five equispaced intersecting radial slots 3.4 mils wide by 25 mils long, as illustrated in FIGURE 4a. In the process of fabrication the counterbore bottoms of two capillaries were inadvertently bent inward from the spinneret face causing a small hump near the middle of the counterbore.

The test spinneret was installed in a conventional grid-melter spinning machine to produce nominal 15 denier monofilament yarn. Each of the six filaments was wound up separately on two common bobbins, three filaments per bobbin. The yarn was wound at a lineal speed of 461 y.p.m. as the extruding filaments were cooled by air flowing across the filaments at a volume rate of 110 ft.³/min. Nylon 66 polymer containing 0.03% TiO₂ deflusterant and having a relative viscosity of 37 was charged to the spinning unit maintained at 294° C. The extruding filaments appeared quite stable except from the two capillaries with the upset counterbore bottoms; these polymer jets appeared somewhat crooked. Examination of microtomed sections showed that the normally extruding filaments had rather rounded out pentagonal cross sections as illustrated in FIGURE 4b, the two defective capillaries yielded more nearly round irregular sections. Samples of yarn were collected and the spinneret was removed.

After heat cleaning, the test spinneret was reassembled in the spinneret pack. A chrome-iron ball bearing 0.062 inch in diameter was placed in each of the six counterbores. This arrangement provided a minimum unobstructed transverse section in the counterbore of about 3900 sq. mils compared with capillary cross section of 405 sq. mils.

The reassembled spinneret pack was reinstalled in the spinning machine with other operating conditions unchanged. The jets of polymer were now observed to extrude much more nearly straight and stably from the spinneret. Jets from the two defective capillaries continued to be skewed and lopsided, it being apparent that the lateral force on the balls was insufficient to center the ball over the hump on the counterbore bottom. Samples of yarn were collected from the normally functioning capillaries. The cross section of the filaments was now a distinctly formed 5-point star as illustrated in FIGURE 4c.

Samples of yarn were drawtwisted at a draw ratio of 4.23, and the 15-denier filaments were knitted into tubes

on a circular knitting machine. The degenerate pentagonal filaments had more luster but practically the same cover as standard circular filaments. But the 5-point star filaments spun with balls in the counterbores had greater cover and a more desirable subdued luster and dryhandle; other tests indicated that these filaments also had superior snag resistance in hosiery.

Example III

10 A standard type 430 S/S spinneret blank 2.03 inch in diameter by 0.189 inch thick was used for a 6-hole spinneret to produce monofilaments having a 10-lobed or 10-point star cross section. The general form of the orifice cross section is illustrated in FIGURE 5a. In order to insure uniform slot length by the particular method of spinneret manufacture, a central circular hole 20 mils in diameter was first drilled. Ten equispaced radial slots, 3 mils wide by 40 mils long, were then formed, giving an overall slot length of 50 mils measured from the center of the orifice. Counterbore diameter was 0.109 inch and capillary length was 17 mils; the counterbore bottom was flat.

15 The above-described 6-hole spinneret was assembled in a standard spinneret pack and was installed in a conventional melt spinning machine equipped with a grid melter. Standard dried nylon 66 polymer flake containing 0.03% TiO₂ and having a relative viscosity of 37 was charged to the spinning machine. The extruded filaments were cooled by air at 23° C. and flowing transversely at a rate of 62 ft./min. Each of the six filaments were wound up individually upon bobbins at a speed of 461 y.p.m. Polymer flow through each capillary was at the rate of 2.75 gms./min. The spun filaments were subsequently drawtwisted at 3.93 draw ratio to yield nominally 15 denier monofilaments.

20 Under the operating conditions described, filaments extruded satisfactorily, but the cross section of the filaments was virtually circular. Spinning unit temperature was reduced from normal 293° C. down to the lowest operable temperature of about 286° C. in order to increase polymer melt viscosity and increase the quenching rate. Even under these extreme conditions, however, the filament cross section was only just perceptibly noncircular as illustrated in FIGURE 5b. In knitted tubes these filaments were scarcely distinguishable from standard circular section filaments.

25 The 10-point star spinneret was removed from the spinning machine, cleaned, and reassembled with a stainless steel ball placed in each counterbore; the ball diameter was 50 mils. The minimum unobstructed free transverse area in the counterbore was about 7400 sq. mils compared with the orifice cross section of about 1500 sq. mils.

30 The spinneret pack with balls in the counterbores was reinstalled in the spinning machine with previously mentioned normal spinning conditions. The polymer jets now extruded in a much straighter path and filament action in the quenching chimney was very steady. Cross sections of the filaments observed under a microscope at 66 $\times$ was seen to have very clearly defined lobes or crenulations as illustrated in FIGURE 5c. When knitted into hosiery these filaments imparted a highly attractive soft silky sheen altogether different than that of standard circular filament yarns.

35 According to the invention a simple expedient extends the range of shape definition possible for a given spinneret orifice under practical operating spinning conditions. It is particularly applicable to orifices comprised of multiple intersecting slots, such as Y-section, cruciform, star, and like sections. The invention is applicable to wet spinning and dry spinning but is especially useful in melt-spinning. Specific polymeric materials capable of being melt-spun include nylon-66 (polyhexamethylene adipamide), nylon-6 (polycaprolactam), nylon-4, nylon-610, nylon-11 and their filament-forming copolymers; e.g., nylon-6/66,

nylon 6/610/66, etc.; polyesters derived for example from terephthalic acid or derivatives thereof and ethylene glycol; polyethylene and polypropylene; and other fiber-forming substances. With an appropriate molten polymer distribution system the spinneret herein can be used to produce multi-component filaments having an eccentric arrangement of dissimilar polymers. The actual dimensions of the openings and ball depend, of course, upon the characteristics of the polymer, the filament size or denier, the spinning speed, the temperature, and other factors in the particular spinning process.

It is apparent from the foregoing description that this invention represent a substantial advance in the art of spinneret and textile yarn manufacture. The spinneret can be made with facility. The art is now provided with an inexpensive and surprisingly simple means of redistributing the spinning fluid flow in noncircular capillaries whereby the degree of definition of the resulting noncircular filament is very significantly changed although spinning conditions and the orifice cross section are left unchanged, this being accomplished by simply placing a spherical ball in the fluid path immediately upstream of the spinneret. Other advantages may be noted.

It is apparent that many different embodiments of the invention can be made without departing from the spirit and scope thereof; and, therefore, it is not intended to be limited except as indicated in the following claims.

What is claimed is:

1. A spinneret for making filaments of noncircular cross section comprising a solid plate having a spinning fluid delivery face and an extrusion face and having at least one orifice extending between said faces to provide a passageway for said fluid, said orifice defined by a bounding wall and having a portion of larger cross-sectional area adjacent the delivery face and a portion of smaller

5

35

cross-sectional area adjacent the extrusion face, the bounding wall at the extrusion face enclosing a plurality of elongated slots, and a spheroid disposed in the delivery face portion of the orifice to divert the flow of the spinning fluid toward the extremities of the elongated slots.

2. A spinneret for melt-spinning filaments of noncircular cross section comprising:

- (a) a solid plate having a melt face and an extrusion face and having at least one orifice extending between said faces to provide a passageway for molten polymer;
- (b) said orifice defined by a bounding wall and having a portion of larger cross-sectional area adjacent the melt face and a portion of smaller cross-sectional area adjacent the extrusion face;
- (c) the bounding wall at the extrusion face enclosing a plurality of radially elongated slots; and
- (d) a solid spheroid disposed in the melt face portion of the orifice to divert the flow of the spinning fluid toward the extremities of the elongated slots.

3. The spinneret of claim 2 wherein the number of elongated slots is 3-10.

4. The spinneret of claim 3 wherein a plurality of orifices are present each with a spheroid therein.

5. The spinneret of claim 4 wherein the orifice portion of larger cross-sectional area is generally cylindrical.
